MASONRY GUIDELINE HOLDER

William H. Batchler, Graham, Tex.

Application July 22, 1948, Serial No. 40,177

5 Claims. (Cl. 33—85)

1

This invention relates to improvements in masonry guide line holder, and more particularly to masonry guide line holders that may be effectively attached, removed or tightened or loosened by the use of one hand.

Various masonry line holders have been proposed heretofore, but these, for the most part, were complicated in structure, which required considerable adjusting and regulating to enable the masonry guide line holder to be properly used or, on the other hand, other masonry line holders that appeared to be simple in construction have been proposed, but the manner of regulating these has been difficult and usually required the use of both hands on the part of the workman and required the removal of the holder from the masonry to tighten or loosen the line, and have not met with popular approval among the trades.

In the present invention, a masonry guide line holder is provided which may be made of cast aluminum or other light weight material, and which has an actuating element so that the line is readily clamped in any desired position, or tightened readily without the necessity of the removal of the line guide holder from the masonry.

The primary object of this invention is to provide a masonry guide line holder that will hold a masonry guide line taut and which may be readily installed, removed or tightened without disturbing the relative position of the holder with respect to the masonry.

Another object of this invention is to provide a masonry guide line holder that is light in weight, easy to use and which may be operated with one hand.

Another object of this invention is to provide a masonry guide line holder that is simple and easy to construct, positive in operation and capable of being secured firmly in place for use.

An embodiment of this invention is illustrated in the accompanying drawings, in which:

Fig. 1 is a perspective view of the invention showing a masonry guide line in place;

Fig. 2 is a cross sectional view taken on the line 2—2 of Fig. 3, looking in the direction indicated by the arrows;

Fig. 3 is a side elevational view of the masonry guide line holder with parts broken away and shown in section and showing the masonry guide line in place; and with the guide line lever shown as released in dot-dash outline;

Fig. 4 is an end elevational view taken from the 55

2

end opposite that is shown in Fig. 2, and showing a masonry guide line in place; and

Fig. 5 is a top plan view of a portion of a building, showing a pair of masonry guide line holders in place on a building with a masonry guide line positioned therebetween.

With more detailed reference to the drawing the numeral 1 designates a body, which may be of cast aluminum, wood, or other suitable material.

10 The body 1 has a medial, longitudinal groove 2 along a face thereof, which groove is adapted to receive a masonry guide line 3. The masonry guide line 3 is of such size that the inner face 4 of the body 1 will be tangent to the line when the line 3 is positioned therein.

15 A pair of upstanding lugs 5 are formed integral with the body 1, one on each side of one face thereof and spaced apart to admit of the line 3 being passed therebetween. A reentrant lever 6 is pivotally mounted on pin 7, which pin passes through lugs 5 and lever 6. An end portion 8 of the lever 6 is rounded at its outer extremity for engagement with the line 3, so as to press the line 3 against the plane face 9 of the body 1. The other end portion of the lever 6 forms a re-entrant extension 10, which extension 10 has a hole 11 therein at right angles to the pivot member 7 of the lever 6. The hole 11 is in axial alignment with groove 2 when the lever 6 is in clamping position.

20 A line 3 is adapted to pass along and within groove 2 and between the outer extremity 8 of the lever 6, and through hole 11, as will best be seen in Fig. 3. When swung into position as indicated in dot-dash outline in Fig. 3, there is sufficient clearance between the rounded end portion 8 of the lever 6 and the plane face of the body 1 to permit the line 3 to slide therebetween. A stop 12 is positioned through lugs 5 so as to limit the movement of lever 6, as indicated in the dot-dash outline Fig. 3. The lever 6 is moved by grasping the line 3 exteriorly and adjacent lever extension 10 and moving the lever into the position as shown in dot-dash outline in Fig. 3 to permit the movement of the line 3 longitudinally for tightening or loosening the line 3. In this manner the line may be pulled tight to swing in position as shown in full outline in Fig. 3, which will cause the rounded end of the lever extension 25 8 to frictionally engage the line 3 with a cam action so as to secure the line 3 in the desired adjusted position.

30 It is preferable to use a pair of these masonry guide line holders, as shown in Fig. 5, with the line 3 drawn taut therebetween. This makes pos-

sible the aligning of brick B or other masonry pieces in an aligned course. When the course has been completed and the next course is started, the masonry guide line holders are moved up the desired distance and the line 3 tightened, as described above, to make possible the maintaining of the course in the correct aligned arrangement.

The upstanding lugs 5 are adapted to form hooks which engage the opposite corners of the masonry B, as indicated in Fig. 5. It is preferable that the upstanding lugs 5 form an angle less than a right angle with the face 4 of the body 1, as will best be seen in Figs. 3 and 5, so that any irregularities that may exist on the corners of the brick B or other masonry will not interfere with the proper setting of the holders for the guide line.

The holder may be readily operated by a single hand, leaving the other hand free to handle brick, tools or the like. After the line 3 has been tightened, a swing of the line will cause the rounded end of lever extension 8 of the lever 6 to frictionally engage line 3 against the plane face 9 of the body 1.

The masonry guide line holder is simple in construction, small and light in weight, very compact and with a minimum of parts, so that it is readily carried in a tool box, and may be readily placed in adjusted position to hold the guide line for the masonry course. The holders may be removed from the course with little effort, but it is not readily dislodged once it is properly placed on the masonry and the line 3 tightened. The masonry guide line holder holds the guide line and the inner face of the holder in true aligned position, when a line of the proper size is used.

I claim:

1. In a masonry guide line holder, a body having a wall engaging face, a medial, longitudinal groove in said face adapted to receive therein a masonry guide line, a pair of upstanding lugs positioned on opposite sides of said groove, a line engaging member pivotally supported between said lugs, said member having an end portion adapted to engage said line in one position of said member and to disengage said line in another position of said member.

2. In a masonry guide line holder, a body having a wall engaging face, a medial, longitudinal groove in said face, adapted to receive therein a masonry guide line, a pair of upstanding lugs positioned on opposite sides of said groove, a line engaging member pivotally supported between said lugs, said member having a clamping portion adapted to clamp said line in said groove in one position of said member and to disengage said line in another position of said member, said member also having a hole for the passage of said line therethrough, said hole being disposed in

alignment with said groove when said clamping portion of said member is in clamping position.

3. A masonry guide line holder comprising a body having a wall engaging face, a medial longitudinal groove in said face adapted to receive a masonry guide line, a pair of upstanding lugs on said body at opposite sides of said groove, a line engaging member pivotally supported between said lugs, said member having a portion operable by movement of said line to rotate said member in one direction to clamp said line in said groove and in another direction to release said line, said portion in the clamping position of said member being in alignment with said groove.

15 4. In a masonry guide line holder, a body having a wall engaging face, a medial longitudinal groove in said face adapted to receive a masonry guide line, a pair of upstanding lugs on said body at opposite sides of said groove, at least one 20 of said lugs having a portion adapted for engagement with a masonry surface positioned at substantially a right angle to said wall engaging face, said portion being disposed at an acute angle with respect to said face, a line engaging 25 member pivotally supported between said lugs adapted by rotation in one direction to clamp said line in said groove and by rotation in another direction to release said line, and means on said member cooperable with said line for rotating 30 said member, said means in the clamping position of said member being in alignment with said groove.

5. In a masonry guide line holder, a body having a wall engaging face, a medial, longitudinal groove in said face adapted to receive a masonry guide line, a pair of upstanding lugs positioned at one end of said body, said lugs forming a hook member having a wall engaging portion disposed at an acute angle to said wall engaging face, and 40 a line engaging lever operatively positioned between said lugs and having an end adapted to clamp a masonry guide line positioned in said groove to said body.
